DESIGN FOR A LADY'S BELT OR SIMILAR ARTICLE

Eirane Mynors, Washington, D. C., assignor to Stelzer Brothers, Inc., a corporation of New York

Application January 16, 1943, Serial No. 109,277

Term of patent 7 years

To all whom it may concern:

Be it known that I, Eirane Mynors, a subject of the King of Great Britain, residing in Washington, in the District of Columbia, have invented a new, original, and ornamental Design for a Lady's Belt or Similar Article, of which the following is a specification, reference being had to the accompanying drawing, forming part thereof.

Fig. 1 is a face view of the belt before it is curved to fit the wearer;

Fig. 2 is a front perspective view of the belt, showing in full lines the essential features of my new design;

Fig. 3 is a fragmentary back view of the clasp portion of the belt of Fig. 2; and

Fig. 4 is a fragmentary top plan view of the disclosure of Fig. 3.

I claim:

The ornamental design for a lady's belt or similar article, as shown and described.

EIRANE MYNORS.
